UNITED STATES PATENT OFFICE.

THOMAS PERKS, OF KEIGHLEY, ENGLAND, ASSIGNOR TO GEORGE HATTERSLEY AND SONS LIMITED, OF KEIGHLEY, ENGLAND.

DETECTOR DEVICE FOR WEFT-REPLENISHING MECHANISM OF LOOMS.

1,130,329.

Specification of Letters Patent.

Patented Mar. 2, 1915.

Application filed February 12, 1913. Serial No. 747,934.

To all whom it may concern:

Be it known that I, THOMAS PERKS, a subject of the King of Great Britain, and resident of 134 Grange View, Lawholme Lane, 5 Keighley, in the county of York, England, have invented a certain new and useful Improvement in Detector Devices for Weft Replenishing Mechanism of Looms, of which the following description, wherein reference 10 is made to the accompanying sheets of drawings, is a specification.

It relates to detector devices for weft replenishing mechanism for looms having change shuttle boxes, such shuttle boxes having more than one compartment being arranged 15 to move and bring each compartment in alinement with the shuttle race on the lay so that the shuttle that has to be ejected therefrom or that has to be received therein 20 will keep in its proper path in manner well known.

My invention has more especial reference to change boxes of the type known as "drop boxes" and particularly I shall hereinafter 25 describe my said invention with reference to this type of shuttle box having two compartments from which description it will be understood that my invention may be extended to shuttle boxes having more than two compartments by the employment of modifications suitable to meet the requirements of the additional compartments.

In the accompanying sheets of drawings which are illustrative of my said invention:—Figure 1 is a front elevation of sufficient structure of a loom and its shuttle box mechanism to illustrate the application thereto of my invention. Fig. 2 is an end elevation partly in section of the parts shown by 40 Fig. 1, this figure being drawn to a reduced scale. Fig. 3 is a similar elevation to Fig. 2 but illustrates certain of the parts in altered positions and this figure is drawn to an enlarged scale. Fig. 4 is a similar view to 45 Fig. 3 but illustrates certain of the parts in other positions as hereinafter explained. Fig. 5 is an elevation of the detector showing same in engagement with a part hereinafter described. Fig. 6 is a plan of parts illustrated by Fig. 5.

A indicates the end frame of the loom, B the shuttle boxes and C the lay of said loom.

The type of shuttle box in connection with which I have elected to describe my invention is that wherein two compartments 2, 3,

are made use of, said compartments being operated by their operating mechanism acting continuously, that is to say, the compartment 2, at one time will be level with the shuttle race, at which time its shuttle may be 50 thrown across from such shuttle box and returned to be received by said shuttle box, while for the next two shots of weft the compartment 3 will be level with the shuttle race, so that in like manner its shuttle may 55 be received and actuated as described. Any well known mechanism is employed for effecting the movements of said shuttle boxes B by actuating the connecting rod 4 which is secured to the lower end of said shuttle 60 box B and which extends to be guided by its guiding bracket 5 within which it is moved or operated by the link 6 coupling it to the lever 7 this latter having at its other end a connecting rod 8 reaching into connection 75 with the actuating devices which as stated may be of any known and common kind.

In connection with each of the compartments 2 and 3 I arrange a detector a, a¹ respectively such detector being arranged to 80 slide through the back part b forming the framework or shuttle box back, the other end of the detector a or a¹ being arranged to slide through a guiding bracket 10 where normally it is pressed forward when free by 85 its respective spring c or c¹. The bracket 10 which supports the detectors a, a¹ is fixed upon so as to move with the shuttle box B, hence the detectors at all times are opposite to their respective shuttles d, d¹ when in 90 their proper compartments and one essential feature of the actions of these detectors a, a¹, is that they are always brought into action to enter the shuttle box and contact with the weft within their respective shuttles during 95 the time that the shuttle boxes B are moving to bring one compartment 2 or the other 3 level with the shuttle race. In other words, assuming that the shuttle d has arrived within its compartment 2 the detector a is 100 allowed to enter said shuttle d immediately the shuttle box commenced to ascend and the effective detection or indication of the condition of the weft therein as to whether same has been depleted or withdrawn therefrom to a predetermined extent, is determined by such detector during the motion of the box B as it is traveling with its compartment 2 from the lower to the higher position. The detector a at such time is 105 110

only permitted to move into the compartment 2 when said compartment begins to rise and slightly before said compartment 2 reaches its other and highest position the detector a will have been withdrawn. As 5 means whereby the detectors a and a^1 are thus enabled to move into and out of the shuttle box at the proper time relatively with the movement of the said shuttle box, I 10 arrange their springs c , c^1 , as before stated, to always tend to press them to enter their respective compartments, while mounted to slide through brackets f^1 , f^2 , I arrange a double incline sliding piece or bar f , the 15 inclines f^1 , f^2 of which act respectively upon the antifriction bowls c^2 , c^3 carried by the detectors c , c^1 . This sliding piece f is caused to rise and fall in unison with the movements of the shuttle boxes by the connecting rod g connected with the piece f and with a lever g^1 which is pivoted at g^2 to the bracket 20 13 carried by the swing rail 14, upon which is mounted the laysword 15.

The lever g^1 is caused to oscillate on its 25 pivotal pin g^2 by a projecting ear k , secured to the vertical box-operating rod 4 so that as said rod 4 rises and descends to lift and depress the shuttle box B said ear k also rises and descends with it. The ear k extends laterally from the rod 4 so that it projects between spaced apart pins h and h^1 which are fixed upon and extend laterally from the lever g^1 .

As the lever g^1 oscillates about its pivotal 35 center g^2 it is necessary that it should be kept in its extreme position during the time that the ear k is moving after leaving the pin h and before it reaches the pin h^1 , or vice versa. To effect this temporary arrest 40 the lever g^1 has a pendant arm g^3 which extends so that a runner g^4 mounted thereon may press upon the buffer or leveling device m , causing same to recede (when passing over its central part) and compress its spring m^1 . When the runner g^4 has passed 45 said central part the recoil of the spring m^1 will force the device m vertically and will so retain the runner g^4 and its lever g^1 in the position they have last assumed; thus it retains the lever g^1 in its raised position at one time, as shown by Fig. 1, as well as in its lowest position (not illustrated) at another time. The lever g^1 is raised by the ear k into the position shown by Fig. 1 by contact of said ear with the pin h which is fixed 50 to said lever g^1 and when the lever g^1 is so raised the rod 4 will have lifted the shuttle box to its highest position. The next movement of the rod 4, to bring the shuttle box 55 into its lowest position, will commence from the position referred to, but the ear k will leave the pin h and will move through half the space traversed by the rod 4 when moving the shuttle boxes to their lowest position, before said ear comes in contact with

the pin h^1 . The remaining half of the motion of the ear k after contacting with said pin h^1 will carry said pin h^1 through the desired distance to move the lever g^1 to its lowest position. These movements of the lever g^1 relatively to the ear k leave the parts actuated by the lever g^1 at rest during a certain portion of the movements of the shuttle boxes B.

The portion of movement of the shuttle 75 box B during the time that the lever g^1 is at rest is that which is midway between its highest and lowest positions. At this time the incline f^1 or f^2 , as the case may be, permits the feeler a or a^1 to pass into said 80 shuttle box to contact with the weft in the shuttle. During the continuation of the motion of the shuttle box from said mid-position to either of its extreme positions (that is, the position at the top or at the bottom 85 of its path) the incline f (as it is actuated by the rod g and lever g^1) will have moved so as to withdraw said feeler a or a^1 from within the shuttle box. In this manner said withdrawal is effected simultaneously with 90 the arrival of the shuttle box at its said extreme position. As an example, when the shuttle box is moved from occupying its highest position down to occupy its lowest position, during the time that the compartment 2 is in or about its middle position, the detector a will be permitted to enter said compartment 2 by reason of the incline f being at this time in the position shown by Fig. 3. The incline f is then brought down 95 from its said position into its lowest position and this is effected by the ear k contacting with the pin h^1 on the lever g^1 so that said lever g^1 by the rod g may actuate the incline f to cause the surface f^1 to force out 100 the bowl c^2 and therefore the detector a . The movement of the ear k in the opposite direction has a like effect, since it will move through half the length of its upward path from being in contact with the pin h^1 before 105 it will come into contact with the pin h so that in this case also the compartment 3 will have been raised from its lowest position half way toward its highest position (that is level with the lay) where it will have 110 allowed the detector a^1 to enter said compartment, its said advancement into said compartment being permitted by the incline f^1 being stationary during the time that the compartment 3 was moving through half its space. The withdrawal of the detector a^1 from its said advanced position is effected 115 by the incline f^1 being raised during the movement thereof through the remaining hold of its path which movement is completed by the time the compartment is finally brought to rest in the position described.

Fig. 3 shows the compartment 2 as half way between its highest and lowest positions at which time the detector bowl c^2 has been 120

allowed to descend the incline f^2 and is therefore forced by its spring c to enter the shuttle d whereas by the shuttle box B continuing in its motion until its lowest position is reached then the incline f will have descended so far as will bring the incline part f^2 into the position shown by Fig. 4, where it will have withdrawn the detector a from the shuttle and the shuttle box, thus 5 at this time the shuttle may be freely actuated by the picking mechanism without interfering in any way with the detector a , while the time occupied by the shuttle box moving from one position to the other is utilized for bringing into action the detector a . In a similar manner when the shuttle box b rises to carry the compartment 3 from its lowest position up into alinement with the shuttle race then the incline f^4 acts in a 10 similar manner upon the detector a^1 as does the incline f^2 on the detector a above described.

Provided the weft in the shuttle has been depleted sufficiently to permit the detector a or a^1 to advance sufficiently far for a catch piece a^2 or a^3 carried by said detector to engage with the notch p^1 on the rod p or the notch p^2 on the same rod, then as the detector a or the detector a^1 (as the case may 25 be) rises or descends with its respective compartment will by its respective catch piece a^2 or a^3 carry with it the rod p to its highest or to its lowest position.

In Fig. 3 the rod p is shown as being engaged by the catch a^2 and forced into its lowest position so that at this time said rod p causes the lever p^3 to oscillate upon its supporting shaft q , so that this shaft is enabled to carry with it the vertical arm q^1 to 30 the right of its vertical position, at which time the lever r is permitted to oscillate upon its shaft r^1 and descend so that its outer end will come into contact with the bunter s pivoted as s^1 . This bunter s is 35 arranged according to my present invention to actuate the lever s^2 so that this latter may actuate the lever s^3 and so bring the upper end s^4 of said lever clear of the ratchet s^5 . This action permits said ratchet s^5 to 40 descend by its own weight into the path of motion of the continuously operating catch lever t which is arranged to bring into operation the weft replenishing mechanism in manner common and well known, said weft 45 replenishing mechanism being of any well known kind either of the type for supplying weft to the running shuttle or for substituting a weft-supplied-shuttle for a shuttle depleted of its weft.

Provided the weft in either shuttle is not sufficiently depleted to enable its respective detector to carry its catch a^2 or a^3 to engage with its notch in the rod p , then this rod p remains in a central position where it 50 will hold or retain the lever q to support

the lever r by taking beneath the projecting part r^2 formed thereon as is shown by Fig. 2. The lever r is raised from its descended position as shown by Fig. 3 into a position above the lever q^1 by its arm r^3 which carries an adjusting screw r^4 being brought by the motions of the slay board so that said screw r^4 will come in contact with a spring u carried by a bracket fixed to the end frame a . The movements of the rod p so as to bring it 70 also into a central position thereby enabling it to adjust the lever arm q^1 in such position is effected by springs v and v^1 which act upon projecting pins extending from an arm v^2 fixed upon the shaft q . 80

As hereinbefore stated although I have only described my detector mechanism as being used in connection with drop box looms I am aware that it is possible to mount and use same in connection with shuttle boxes that are arranged to oscillate about their axial centers and although I have only shown my devices in conjunction with a shuttle box having two compartments it may be possible to use same with shuttle 90 boxes having a larger number of compartments so that I do not wish to confine myself to the exact details herein described, but

What I do wish to claim is:—

1. In looms having automatic weft replenishing mechanism a movable shuttle box having a plurality of compartments, a detector device mounted upon each of said compartments, means whereby the detector device may be brought into action to contact with the weft in the shuttle and to be withdrawn therefrom during the movements of its respective compartment, and means for actuating said detectors together with devices whereby the indications transmitted through said detectors will cause the actuation of the weft replenishing mechanism, substantially as herein specified.

2. In a loom having automatic weft replenishing mechanism and shuttle boxes with a plurality of compartments, a support movable with the shuttle boxes, detectors slidably mounted in the support so as to be movable at all times with the shuttle boxes, each compartment having its respective detector, a slidable bar engaging the detectors and provided with an offset portion to permit the detectors to enter their respective shuttle boxes, means for actuating the bar, and means whereby the indicating movement of said detectors will cause the actuation of the weft-replenishing mechanism.

3. In a loom having automatic weft replenishing mechanism and shuttle boxes with a plurality of compartments, detectors mounted upon said shuttle box so as to be moved at all times therewith, each compartment having its respective detector, springs for normally pressing said detectors in one

direction, a sliding bar having inclined surfaces for actuating said detectors, a notched rod for engaging with catches carried by said detectors, lever devices whereby said 5 notched rod will bring into action mechanism for automatically effecting the weft replenishing of the loom substantially as herein specified.

4. In a loom having automatic weft replenishing mechanism and shuttle boxes with a plurality of compartments, detectors mounted upon said shuttle box so as to be moved at all times therewith, each compartment having its respective detector, 10 springs for normally pressing said detectors in one direction, a sliding bar having inclined surfaces for actuating said detectors, lever devices for transmitting motion to said inclined sliding bar, and means whereby 15 said lever devices will be operated by the shuttle box operating mechanism, substantially as herein specified.

5. In a loom having automatic weft replenishing mechanism and shuttle boxes with a plurality of compartments, detectors mounted upon said shuttle box so as to be moved at all times therewith, each compartment having its respective detector, springs 20 for normally pressing said detectors in one direction, a sliding bar having inclined surfaces for actuating said detectors, a box-operating rod having a projecting ear, a lever having spaced pins engaging said ear, a rod connecting the lever with the sliding bar, and means for actuating the box operating 25 rod substantially as herein specified.

6. In a loom having automatic weft replenishing mechanism and shuttle boxes

with a plurality of compartments, detectors mounted upon said shuttle box so as to be moved at all times therewith, each compartment having its respective detector, springs for normally pressing said detectors in one direction, means for operating said detectors in the opposite direction to said 45 springs, a notched rod as *p* for engaging with catches upon said detectors, connected lever arms one of which is engaged with said rod, a lever having a projection for operating in conjunction with the other lever 50 arm, and springs for bringing the last mentioned lever arm into a central position substantially as herein specified.

7. In a loom having automatic weft replenishing mechanism and shuttle boxes with a plurality of compartments, detectors mounted upon said shuttle box so as to be moved at all times therewith, each compartment having its respective detector, springs 55 for normally pressing said detectors in one direction, a sliding bar having inclined surfaces for actuating said detectors, a box-operating rod having a projecting ear, a lever having a laterally extending arm, and spaced pins engaging said ear, a rod connecting the lever with the sliding bar, and a spring-actuated leveling device coöperating 60 with said lever arm, substantially as herein specified.

In testimony whereof I have signed my 70 name to this specification in the presence of two subscribing witnesses.

THOMAS PERKS.
